UNITED STATES PATENT OFFICE.

WILLIAM MEADOWCROFT, OF BLACKBURN, ENGLAND.

BOTTLE-FILLING MACHINE.

Application filed July 17, 1923, Serial No. 652,088, and in Great Britain September 19, 1922.

This invention relates to a bottle filling machine of the multiple headed rotary type and has for its chief object to facilitate the adjustment of the machine to take different lengths of bottles, to enable bottles to be automatically transferred to and from bottle rests without colliding with any guards that may be used, to prevent waste of liquid when bottles are not placed in position and to provide an improved form of liquid distribution valve.

According to this invention the rotary filling heads are carried by a vertical member that is arranged to be raised and lowered by suitable mechanism for adjusting the machine to take different lengths of bottles and angularly displaceable divisional bottle guards are used which are adapted to extend between the filling heads and the bottle rests and to be moved above the level of the latter to provide a free passage for the transference of the bottles to and from the bottle rests. The filling heads are so constructed and arranged as to close the communication with the supply until a bottle is raised to make a sealed joint with the mouth of the filling head and a rotary disc type of liquid inlet and air or gas outlet valve is used, the said valve having one stationary member and one rotary member each of which is faced with leather, or other appropriate material, the air or gas outlet valve being fitted with a manually operated adjusting valve to control the amount of air or gas released from the bottles thus regulating the amount of liquid that can enter the bottles.

In order that the said invention may be clearly understood and readily carried into effect, the same is described more fully with reference to the accompanying drawings, wherein:

Fig. 1 is a vertical section partly in elevation of a multiple headed rotary filler constructed in accordance with this invention.

Fig. 2 is a plan of the machine shown in Fig. 1.

Fig. 3 is a horizontal section showing the cams which operate the bottle rests and also the divisional bottle guards.

Fig. 4 is a detail vertical section of a filler head, drawn to a larger scale.

Adverting to Fig. 1 the base casting 1 has a vertical bearing 2 through which a sleeve 3 extends and secured to such sleeve by a key 5 is a worm wheel 4 that is driven by a worm 6 on a shaft 7 which is supported

on the base 1 by bearings 8, see Fig. 3. On the upper end of the sleeve 3 is fixed a revolving table 9 by a key 10 and passing through the sleeve 3 is a vertical shaft 11 that is slidably keyed to the sleeve 3 by a key 12 so that when the sleeve 3 is rotated the table 9 and shaft 11 are rotated also. On the top of shaft 11 is secured a top plate or casting 13 by means of a key 14 and nut 15 so that the casting 13 revolves with the shaft 11. Interposed between the sleeve 3 and casting 13 is a spring 16 which supports the weight of the shaft 11 and is always tending to raise the casting 13 carrying the filling heads 17 and maintain the latter at the greatest distance from the bottle rests 18 for taking the longest bottles. The shaft 11 is screw-threaded at its lower end and on it is screwed a bevel or other wheel 19 gearing with a pinion 20 on a shaft 21 provided with a wheel 22 and supported in a bearing 23 fixed to the base 1. To lower the filling heads 17, the wheel 22 is revolved, thus turning the pinion 20 and bevel or other wheel 19 which then acts as a nut to draw the shaft 11 downwards thereby compressing the spring 16 and lowering the casting 13 and filling heads 17 to suit any required length of bottle. The wheel 19 normally revolves with the shaft 11, and revolves the shaft 21 and the hand wheel 22 idly. On the base 1 is mounted a stationary cam 24 for raising and lowering the bottle rests 18 in a usual manner by means of a roller 25 mounted on a pin 26 in a slide 27 situated within a sleeve 28 containing a spring 29, the said sleeve being slidably mounted in a supporting casting 30 which is carried by the revolving table 9, the spring 29 allowing the sleeve 28 to move down the slide 27 to accommodate bottles which vary slightly in length. On cam 24 is mounted a cam 31 which raises and lowers rods 32 carrying a shoe 33 and a divisional guard 34, the rod 32 sliding through a support 35 fixed to the revolving table 9. The guard 34 Fig. 3, is also rotated through a small angle by the shoe 33 on the rod 32 by means of side wings 31^A and 31^B on the cam 31. These movements are necessary to allow of bottles being automatically placed on to and taken from the bottle rests 18 (Fig. 1) by a machine such as described in the specification of my application for patent of even date herewith or any similar machine. The internal bottle guard is in two portions 36,

37 (Fig. 1) the bottom portion 36 being fixed to the revolving table 9 and the top portion 37 to the top casting 13. The top portion 37 is free to slide over the bottom portion 36 when the top casting 13 is lowered for filling small bottles. The pulley 38 is slideable on the shaft 7 to put the machine in or out of action through a clutch 38^A (see Fig. 3) and is moved by a rod 39 carried by the base casting 1 and operated by lever 40 (see Figs. 2 and 3). To the base casting 1 are attached three pillars 41 carrying at the top a ring 42 on which is mounted a liquid inlet supply valve 43 which is flexibly connected by a flexible tube 44 to a liquid inlet distributing valve 45 which has a port 46 for liquid, of any suitable form, and a release port 47 for gas, the latter being provided with a needle valve 48 for adjusting its area so as to control the amount of air or gas pressure released from the bottles thus controlling the amount of fluid entering the bottles. The liquid inlet distribution valve 45 is held in a stationary position by means of an arm 49 (see Fig. 2) which is slidably connected to one of the pillars 41 by means of a vertical rib 50 cast on such pillar. The liquid inlet distribution valve 45 is faced with a renewable leather or other seating 51 under which is a revolving seat 52 of metal or other suitable material which is also renewable and rotated by a distribution fitting 53 and makes a pressure tight joint with same by means of a suitable jointing washer 54. The distribution fitting 53 has alternate liquid ports 55 and air or gas ports 56 which as the distribution fitting 53 revolves come under a liquid port 46 and a gas or air port 47 in the stationary liquid inlet distribution valve 45, thus in a known manner filling the bottles. The stationary face 51 is kept in pressure tight contact with the revolving face 52 by means of washers 57, 58 and 59 and a lever 60 which screws on to a rod 61 that is attached to the shaft 11, one of the washers, 57 for example, advantageously being a spring or flexible washer. The revolving distribution fitting 53 is rotated by a peg 62 from the top of the shaft 11, thus rotating at the same speed as the filling heads 17. Each of the latter consists of a body 63 fixed to the casting 13 by a nut 64 through which the filling head 17 can slide. On the upper end of the filling head 17 is a valve cap 65 which is pressed on a washer 66 by means of a spring 67 confined between the valve cap 65 and a pressure tight cap 68. The latter is connected with a port 55 in the distribution fitting 53 by means of a nut 69, a tubular connection 70, nut 71, and pipe 72. The filling head 17 is also coupled flexibly

to a port 56 by a nut 73 and pipe 74. The mouth of the filling head is fitted with a rubber joint washer 75 that is held in position by a nut 76. Each filling head is prevented from rotating by a peg 77 screwed into the casting 13. When there is no bottle on the bottle rest 18, the filling head 17 remains down with the valve cap 65 making a pressure tight joint on the washer 66 thus when the ports 46 and 55 coincide, no liquid can run through the filling head 17 but when a bottle is placed in position on the bottle rest, the filling head 17 is raised owing to the cam 24 forcing the bottle upwards and lifting the valve cap 65 off the washer 66 and simultaneously pressing the washer 78 against the body 63, thus making a pressure tight joint. When the parts are in this position the liquid can enter the bottle as soon as the ports 46 and 55 coincide and the filling can then take place in a known manner through a passage 79 in the filling head 17, the air or gas being allowed to escape through a port 80, nut 73, pipe 74, ports 56 and 47 and needle valve 48. The machine is suitably guarded by guards 81, 82, 83 and 84, pivoted to the pillars 41, the two guards 82 and 83 being made to open in a doorlike manner by handles 85 and 86 but when closed they are rigidly held by catches 87 and 88.

What I claim as my invention and desire to secure by Letters Patent in the United States, is:

1. In a bottle filling machine, a support provided with a vertical bearing, a sleeve journaled in the bearing, a table secured to the sleeve and provided with bottle rests, a shaft splined to the said sleeve and revolving with it and the table, a top plate secured to the said shaft and provided with bottle filling heads, a spring supporting the said top plate and shaft, adjusting devices for raising and lowering the shaft and top plate, and driving mechanism for revolving the said sleeve.

2. A bottle filling machine as set forth in claim 1, and having also a nut screwed on the lower end portion of the said shaft and operating to lower it against the upward pressure of the said spring.

3. A bottle filling machine as set forth in claim 1, the said filling heads being provided with automatic valves for liquid which are opened when the bottles are raised, and said machine having also lifting mechanism which raises the said bottle rests and the bottles as the said table and shaft are revolved.

In testimony whereof I affix my signature.
WILLIAM MEADOWCROFT.
